ATTACHMENT FOR SEWING MACHINES

Alexander Soltan, Elmhurst, N. Y., assignor to
Novelty Slipper Co., Inc., New York, N. Y., a
corporation of New York

Application March 6, 1935, Serial No. 9,542

12 Claims. (Cl. 112—34)

My invention relates to sewing machines, and more particularly to attachments for use upon a chain stitch sewing machine to be used in the assembling of turned shoes.

5 In the production of turned shoes, a sole having an integral welt, formed by what is called a "seam channel", upon the flesh side of the sole, is formed partially or wholly about the edge of the sole, this edge of the sole having an edge channel 10 outside of the bottom of the seam channel. The free edge of the welt is directed inwardly of the edge of the sole.

Prior to my invention, several practices were followed in attaching the upper of a shoe to the sole. The first of these consisted in securing the sole, flesh side outwardly, to a last. Thereafter the upper was lasted in relation to the sole in the usual manner. During such lasting, the upper was inside out, and after the completion of the 20 lasting operation of both the sole and the upper, these parts were sewed together by means of an ordinary Goodyear shoemaking sewing machine, the stitching being done while the parts were upon the last. This practice involved the lasting 25 of the shoe parts before stitching, the removal of the shoe from the last after stitching and the turning of the upper, and the re-lasting of the shoe, usually with a slightly oversize last, prior to the finishing operations upon the shoe.

30 Another method consisted in turning the edge of an ordinary integral welt sole upon itself so as to cause the integral welt to be directed outwardly of the sole. To permit this turning, the integral welt had to have slots cut therein about the toe and at the sides of the fore-quarter of the sole, so that gores would be formed when turning the welt in the manner described. The sole thus turned was placed grain-side down with the edge of the sole resting upon the edge of the upper, and the parts sewed together with an ordinary straight needle sewing machine similar to the McKay machine. No pre-lasting of the shoe parts was required by this method. After the stitching of the sole and the upper, the upper was turned and during this turning, the edge of the sole which had been turned upon itself, was restored to its normal position. Thereafter the shoe was lasted before giving the shoe its final finish.

50 In this method of making a shoe, the turning of the edge of the sole and returning it to its former position, were slow, troublesome operations and deformed the leather of the sole about the edge thereof in a manner to weaken the sole at this point and present serious difficulties in

imparting a desired finish to the sole during the finishing operation. Furthermore, the cuts in the welt, to permit the turning of the edge of the sole and the welt, interfered with proper stitching about the toe at the sides of the fore-quarter 5 of the sole. During the stitching operation the sole and the welt were positioned between the operator and the edge of the upper, making the accurate fitting of the upper to the welt difficult if not impossible. Furthermore, when turning 10 the upper, the edge of the upper and its lining and the welt were liable to become crumpled, particularly about the toe of the shoe, so as to interfere with the lasting of the shoe preparatory to the finishing operations.

15 There has been recently developed a third method of making a turned shoe in which the usual integral welt sole has the edge of an upper, while inside out, folded over the edge of the sole and laid upon the welt, the sole and the upper being fed edgewise in relation to the stitching mechanism of a sewing machine. By this method, both the grain and the flesh sides of the sole are exposed to the operator and match markings may be used upon these parts and 20 brought into accurate register so as to secure the accurate fitting of the upper to the sole. Furthermore, by this method, there is no material distortion of the edge of the sole, and after the stitching operation, the welt with the edge 25 of the attached upper, will be brought flat within the shoe, due solely to the turning of the upper. Consequently there is no crumpling of the welt or of the edge of the upper within the shoe, and the only lasting operation, preparatory to the 30 finishing of the shoe, will complete the flattening of the welt and the edge of the upper and no difficulty will be experienced during this lasting operation.

35 With the above conditions in mind, I have 40 produced certain attachments which may be applied to any well known type of chain stitch sewing machine by means of which the sole may be accurately held edgewise in relation to the awl and the needle of said stitching mechanism. The 45 stitch channel will be spread to provide space for the formation of the stitch and the proper location thereof, and the edge of the upper will be accurately laid across the edge of the sole upon the welt.

50 The attachment is also so formed that it will automatically adjust itself to the changing contour of the edge of the sole and to the slight flaring of the edge of the sole by the presser foot of the machine.

The sole guiding mechanism is so constructed that in the event of accident during the stitching operation, it may be quickly removed from its relation to the sole and the upper to permit the removal of the shoe in process from the machine.

The invention consists primarily in an attachment for a sewing machine having a needle and an awl, said attachment embodying therein a base adapted to be mounted at one side of the stitching mechanism, a vertically extending spreader spaced from said base toward the needle and the awl, a sole guide in advance of said spreader, and a movable presser foot co-operating with said spreader; and in such other novel features of construction and combination of parts as are hereinafter set forth and described, and more particularly pointed out in the claims hereto appended.

Referring to the drawing, Fig. 1 is a perspective view of a fragmentary portion of the stitching mechanism of a chain stitch sewing machine embodying therein the attachment of the invention;

Fig. 2 is a side view of the attachment including the presser foot in its raised position;

Fig. 3 is an end view of the attachment as shown from the left of Fig. 2; and

Fig. 4 is a detail view of the sole guide member removed from the attachment.

Like numerals refer to like parts throughout the several views.

In the embodiment of the invention shown in the drawing, it is illustrated in connection with an old and well known type of sewing machine, the stitching mechanism of which includes therein an awl 10, a needle mechanism 11 including a needle 12, a rest 13 at one side of the awl and the needle mechanism and a thread guide or looper 14. These elements are all old and well known in sewing machines, the invention not residing in these parts of the sewing machine but in the combination therewith of an attachment by which the sole of a shoe having an integral welt, is positioned with the edge thereof in a horizontal plane so as to permit a rapid, convenient and accurate assembly of the upper in relation to the sole. The rest 13 has a dovetail slot, the undercut being shown at 15, such dovetailed slot being used in the ordinary machine to support a bracket carrying the work plate.

Mounted upon said rest is a base 16 having a slide 17 adapted to dovetail with the undercut 15 and to be locked in position by a set screw 18.

Projecting from the slide 17 is a spreader 19 having a transversely rounded wedge 20 upon the face thereof presented towards the base 16, and a channel 21 on the other face thereof, which channel affords clearance for the reciprocation of the awl 10 and the needle 12. The top of the spreader is reduced to a narrow edge in order to permit the spreading of the seam channel forming the integral welt of the sole, and to permit a limited lateral movement of the free edge of the welt and the proper positioning of the lower edge of the shoe upper in relation to the spread welt without possibility of mutilation of the welt.

The face of the base 16 presented toward the spreader is bevelled or undercut from the top downwardly, and is spaced from the wedge 20 sufficiently to provide clearance for the spread welt and the lower edge of the upper, and to properly position same in relation to each other in their overlying relation during the stitching operation and the feeding of the sole and the upper by the needle during such operation.

A presser foot 22 co-operates with the spreader 19 and differs from the ordinary presser foot in the respect that one side thereof is provided with a bevel 23 so as to conform to the angle of the welt and of the edge of the upper resulting from the spreading action of the wedge 20. The opening in the presser foot is elongated and, in part, is in alignment with the channel 21 of the spreader bar. In this manner, a clear path is afforded for the movement of both the awl and the needle 10 mechanism between the bottom of the channel 21 and the bottom of the seam channel of the sole of the shoe, which is spaced from the bottom of the channel 21 by the sides of this channel and for movement of the needle in relation to the 15 presser foot during the feeding of the shoe parts.

Carried by the top of the base 16 is a stop plate 24 having the end toward the spreader plate rounded at 25 for the purpose of guiding the lower edge of the upper during the feeding movement 20 of same and of the sole.

Pivotedly mounted upon the base 16 is a sole guide 26 held upon the base by a pivot screw 27 having an enlarged head. Positioned between this head and the top of the sole guide is a compressible spring 28 permitting play of the arm toward and from the base 16. The screw threaded portion of the pivot screw has a loose fit with the co-operating screw threads in the slide 17, and the opening through the base 16 for said 30 pivot screw is of greater diameter than said screw, so as to allow a limited tilting movement of the screw during the play of the guide arm. The spring 28 has a wide base engaging the sole guide 26 to permit this tilting movement and lacks 35 strength to bind the screw threads of the pivot screw 27 with the co-operating screw threads in the slide 17. The sole guide may have free turning movement upon said pivot screw.

To prevent accidental turning movement of the 40 sole guide 26, I provide the base 16 with a stud 29 adapted to enter a socket 30 in the under face of the guide, this stud being of a height to normally prevent turning of the arm without relieving the tension of the spring 28.

The sole guide 26 is provided with an extension 31 having a channel 32 therethrough, the bottom of this sole guide being on substantially the same plane as the top of the spreader, and the channel 32 being of a width corresponding 50 substantially with the distance between the bottom of the seam channel in the sole and the edge of the sole.

The end of said channel 32 remote from the spreader 19 is rounded, as at 33, with the two-fold object of preventing any scraping of the edge of the sole contacting therewith and to co-operate with the sole in imparting lifting movement or vertical play of the sole guide in a manner to be hereinafter referred to.

Projecting from the end of the extension 31 close to the outer side of the channel 32 is a horn 34, the face of which presented toward the base, is rounded throughout its upper portion so that the presser foot 22 may move the edge of the sole away from the spreader and suitable pressure by said foot may be developed upon the welt and the channelled edge of the sole. This action is merely a slight flaring of the edge of the sole which assists the action of the spreader in 70 widening the seam channel. This rounded surface 35 also assists in the proper laying of the edge of the upper over the edge of the sole and upon the welt by the presser foot.

The horn 34 is of a length to project partially 75

across the channel 21 in the spreader and is spaced therefrom a distance approximating the thickness of the sole between the channel forming the integral welt and the grain side of the leather in the sole, while allowing sufficient clearance for a free feeding movement of the two parts of the shoe being assembled. Since the spreader 20 is interposed between the integral welt and the edge of the upper, and the horn 34, no clearance need be provided for such parts in locating the horn.

The bevel or undercut face of the base 16 is shown at 36.

The operation of a sewing machine equipped with the herein described attachment is substantially as follows:—

In assembling a shoe, or other footwear, in which the integral welt extends about the toe quarter of the sole and upon opposite sides of the shank only, the presser foot 22 is raised and the edge of the sole is passed through the channel 32, and the integral welt upon the flesh side of the leather is passed over the spreader 20, thus spreading or widening the seam channel 25 between this welt and the sole proper. The lower edge of an upper is then located in relation to the end of the welt by means of match marks upon the upper. The sole and the upper are advanced slightly to permit them to be engaged by the presser foot 22 in a position where the awl and the needle are operative in relation to the shoe parts. The presser foot is then lowered holding the shoe parts so that the operator may properly position the upper with relation to the edge of the shoe and the welt.

When thus positioning the sole in the attachment, the flesh side is presented toward the spreader 20 and the grain side toward the horn 34 and in loose sliding contact therewith. The edge of the sole should be always in engagement with the bottom of the channel 32 and the grain side of the leather should contact with the horn 34. The edge of the upper passes over the extension 31.

When the presser foot 22 engages the edge of the upper interposed between it and the edge and welt of the sole, the portion of the sole adjacent its edge is flared slightly toward the grain side of the leather or away from the spreader 20. The curved face 35 of the horn 34 permits but limits the extent of this spreading action. Furthermore, with the descent of the presser foot the edge of the upper will be forced against the edge of the sole over which it is folded, and into a parallel relation with the welt throughout the entire width thereof adjacent the wedge 20 and between it and the bevel or undercut face of the base 16. The ordinary elongated opening in the presser foot is in part directly above the awl or needle channel 21 in the spreader.

With the operation of the machine, the sole and the upper are simultaneously fed in the usual manner during the operation of the stitch forming mechanism, and during this feeding movement, the transversely curved wedge 20 and the bevelled guide surface 35 progressively spread the seam channel and fold the edge of the upper in the manner above described. It is merely necessary for the operator to guide the edge of the upper, since the spreader 19, the channelled extension 31 and the horn 34 control the position of the sole during the stitching operation.

While the shank portion of the sole is passing the extension 31, the portion of the sole adjacent

said edge is in the channel 32 and the edge of the sole engages the bottom of said channel 32. As the shank of the shoe passes from said channel, the edge of the fore-quarter of the sole contacting with the rounded portion 33, will raise the sole guide 26 against the tension of the spring 28, the curved surface and the movement of the guide preventing injury or deformation of the edge of the sole. As a result of such vertical play of the sole guide, it is permitted to follow the irregular curve of the contour of the sole and since the upper is fed over the extension 31 of said guide, maintain a proper relative position of the sole and the upper at the guide. During the feeding of the shoe parts, the edge 15 of the sole in advance of the extension 31 and both faces thereof, are exposed to the operator and the associated welt and upper edge may also be observed. By providing match markings at the toe of the sole and of the upper and at 20 opposite sides of the shank portion of the upper, it is possible for the operator to secure a proper fitting of the edge of the sole to the welt by crowding the material of the upper or stretching it slightly so as to secure a proper register of 25 the match markings.

If during the stitching operation, it should be necessary to interrupt the operation of the machine and remove or restore the sole and the upper in relation to the stitching mechanism, the sole guide may be manually raised and swung to one side so as to bring the channel 32, and the horn 34 out of engaging relation with the sole of the shoe and thus permit the shoe parts to be raised from the spreader after the presser foot 35 has been properly elevated and the needle and awl properly positioned to permit this movement. This swinging of the sole guide is an emergency feature and during the normal operation of the machine, the stud 29 engaging with the socket 30 40 prevents pivotal movement of said guide.

The pivot screw 27 may be used to regulate the tension of the spring 28 for controlling the pressure between the bottom of the channel 32 and the edge of the sole. The bottom edge of the upper 45 does not pass through said channel 32, but over the top of the extension 31.

During the feeding of the shoe parts, the extension 31 extends to within the upper.

The dovetail mounting of the base 16 upon 50 the rest 18 permits accuracy in the adjustment of the needle and awl channel 21 in relation to the presser foot and the awl and needle, the set screw 18 maintaining this adjustment. The only other adjustment in the attachment is the 55 pivot screw 27, since it is possible to use a stud 29 of a predetermined height notwithstanding that in the drawing this stud is shown as a screw stud, making it capable of adjustment.

The stop plate 24 prevents pivotal movement 60 of the sole guide 26 during feeding movement of the shoe parts. The lost motion between the screw threads upon the pivot screw 27 and between said pivot screw and the sole guide 26 permits that tilting movement of said guide necessary to allow it to follow the irregularities in the edge of the sole. The conical compression spring 23 with the base of the spring bearing on the guide 26 is used because a wide base spring of this kind is desirable in securing a tilting of the sole guide 26 without developing excessive pressure.

It is not my intention to limit the invention to the precise details of construction shown in the accompanying drawing, it being apparent that 75

such may be varied without departing from the spirit and scope of the invention.

Having described the invention what I claim as new and desire to have protected by Letters 5 Patent, is:—

1. An attachment for a sewing machine having a needle and an awl, said attachment embodying therein a base adapted to be mounted at one side of the stitching mechanism, a vertically extending spreader spaced from said base toward the needle and the awl, a sole guide in advance of said spreader, and a movable presser foot co-operating with said spreader.
  2. An attachment for a sewing machine having a needle and an awl, said attachment embodying therein a base adapted to be mounted at one side of the stitching mechanism, a vertically extending spreader having a wedged surface presented toward and spaced from said base, and a needle and awl channel upon the opposite face thereof presented toward the needle and the awl, a sole guide in advance of said spreader, and a movable presser foot co-operating with said spreader.
  3. An attachment for a sewing machine having a needle and an awl, said attachment embodying therein a base adapted to be mounted at one side of, and having a bevelled surface on the end thereof presented toward the stitching mechanism, a vertically extending spreader having a transversely curved wedged surface presented toward and spaced from said base, and a needle and awl channel upon the opposite face thereof presented toward the needle and the awl, a sole guide in advance of said spreader, and a movable presser foot co-operating with said spreader.
  4. An attachment for a sewing machine having a needle and an awl, said attachment embodying therein a base adapted to be mounted at one side of the stitching mechanism, a vertically extending spreader spaced from said base toward the needle and the awl, a sole guide in advance of and having an extension with a downwardly presented channel in substantial alinement with said spreader, and a movable presser foot co-operating with said spreader.
  5. An attachment for a sewing machine having a needle and an awl, said attachment embodying therein a base adapted to be mounted at one side of the stitching mechanism, a vertically extending spreader spaced from said base toward the needle and the awl, a sole guide in advance of and having an extension with a downwardly presented channel in substantial alinement with said spreader, and a horn at the end of said extension projecting toward and in operative relation to the spreader, and a movable presser foot co-operating with said spreader and said horn.
  6. An attachment for a sewing machine having a needle and an awl, said attachment embodying therein a base adapted to be mounted at one side of the stitching mechanism, a vertically extending spreader spaced from said base toward the needle and the awl, a sole guide in advance of and having an extension with a downwardly presented channel in substantial alinement with said spreader, and a horn at the end of said extension projecting toward and in operative relation to the spreader, said horn having a curved upper edge presented toward said spreader to permit flaring of the edge of the sole away from said spreader, and a movable presser foot co-operating with said spreader and said horn.
  7. An attachment for a sewing machine having a needle and an awl, said attachment embodying
- therein a base adapted to be mounted at one side of the stitching mechanism, a vertically extending spreader having a wedged surface presented toward and spaced from said base, and a needle and awl channel upon the opposite face thereof presented toward the needle and the awl, a sole guide in advance of and having an extension with a downwardly presented channel in substantial alinement with said spreader, and a horn at the end of said extension projecting toward and in operative relation to the spreader, and a movable presser foot co-operating with said spreader and said horn.
8. An attachment for a sewing machine having a needle and an awl, said attachment embodying therein a base adapted to be mounted at one side of, and having a bevelled surface on the end thereof presented toward the stitching mechanism, a vertically extending spreader having a transversely curved wedged surface presented toward and spaced from said base, and a needle and awl channel upon the opposite face thereof presented toward the needle and the awl, a sole guide in advance of, and having an extension with a downwardly presented channel in substantial alinement with said spreader, and a horn at the end of said extension projecting toward and in operative relation to the spreader, said horn having a curved upper edge presented toward said spreader to permit flaring of the edge of the sole away from said spreader, and a movable presser foot co-operating with said spreader and said horn.
9. An attachment for a sewing machine having a needle and an awl, said attachment embodying therein a base adapted to be mounted at one side of the stitching mechanism, a vertically extending spreader spaced from said base toward the needle and the awl, a sole guide in advance of said spreader, means whereby said sole guide is tiltingly secured to said base, a spring resisting tilting movement of said guide, and a movable presser foot co-operating with said spreader.
10. An attachment for a sewing machine having a needle and an awl, said attachment embodying therein a base adapted to be mounted at one side of the stitching mechanism, a vertically extending spreader spaced from said base toward the needle and the awl, a sole guide in advance of said spreader, a pivot screw loosely mounted in said base and having a lost motion bearing with said sole guide, a conical spring engaging said pivot screw and said guide, and a movable presser foot co-operating with said spreader.
11. An attachment for a sewing machine having a needle and an awl, said attachment embodying therein a base adapted to be mounted at one side of the stitching mechanism, a vertically extending spreader spaced from said base toward the needle and the awl, a sole guide in advance of said spreader, means whereby said sole guide is mounted to have vertical play and horizontal rotation upon said base, a spring resisting tilting movement of said guide, a stop plate preventing rotation of said guide in one direction, a stud upon said base, said guide having a socket therein co-operating with said stud, whereby it is permitted to have vertical play, but is prevented from turning in the opposite direction, and a movable presser foot co-operating with said spreader.
12. An attachment for a sewing machine having a needle and an awl, said attachment embodying therein a base adapted to be mounted at one side of the stitching mechanism, a vertically extending spreader spaced from said base toward

the needle and the awl, a sole guide in advance of and having an extension with a downwardly presented channel in substantial alignment with said spreader, and a horn at the end of said extension projecting toward and in operative relation to the spreader, said horn having a curved upper edge presented toward said spreader to permit

flaring of the edge of the sole away from said spreader, and a movable presser foot having a bevelled surface thereon presented toward said horn co-operating with said spreader and said horn.

ALEXANDER SOLTAN.
